UNITED STATES PATENT OFFICE.

CHARLES JEAN NICOUD, OF MARSEILLE, FRANCE.

PICKER-ROLLER.

1,250,491.

Specification of Letters Patent. Patented Dec. 18, 1917.

Application filed July 9, 1915. Serial No. 39,003.

To all whom it may concern:

Be it known that I, CHARLES JEAN NICOUD, citizen of the Republic of France, residing at 22 Allées de Meillan, in Marseille, in the 5 Republic of France, have invented certain new and useful Improvements in Picker-Rollers, of which the following is a specification.

This invention relates to picker rollers 10 and its object is to provide improved picker rollers for use in carding silk waste or other textiles.

In the usual picker rollers, a plurality of pointed members are mounted upon a 15 wooden drum or roller and, in operation, effect a tearing action upon the textile, the chief disadvantage incurred being the doubling of entwined fibers which occasions considerable waste in carding.

20 By means of the present invention this disadvantage is obviated, the slivers for carding obtained thereby including no entwined or bunched fibers or only a minimum thereof.

25 Referring to the accompanying drawings, illustrating the present invention by way of example,

Figure 1 is a side view of the improved picker device;

30 Fig. 2 is a partial top view thereof;

Fig. 3 is a side view of one of the pointed blades according to the invention;

Fig. 4 is a cross section thereof; and

35 Fig. 5 is a cross section of a set of blades mounted on their support.

In place of the usual pointed pickers, pointed blades A, preferably of steel, having each a sharpened-edged upper portion, are mounted in a holder B of bronze or other 40 suitable material, secured to a support K of hard wood or the like which is, in turn, secured to the picker drum C by suitable screws F, the blades being firmly held in position by means of three bolts h. A number 45 of similar supports K are arranged at suitable intervals on the periphery of the drum C. Each support K is preferably provided

near its rear end with a grooved cross piece or channel O of steel, which extends transversely of the periphery of the drum for a purpose to be described hereafter.

The blades are spaced apart so as to form 50 between them a number of channels m, n, for the reception of the fibers of textiles operated upon by the points of the blades, the fibers being carried into and deposited in

the channels without intermixing or entwining occurring between them.

When the torn fibers have thus been deposited in the channels m, n, so as to lie 60 parallel to the pointed blades, the rotation of the drum is stopped.

As a certain number of fibers caught by a set of blades may have become attached to blades of the following set owing to the 65 rapid rotation of the drum during the picking operation, the operator then slowly puts the drum in motion by hand and separates the fibers extending from one set to another by cutting the same by means of a knife 70 drawn through the channel O across the periphery of the drum.

Behind each set of blades, the drum carries a pair of supports E to which is pivoted a swinging fork D which, during the operation of the picker blades, is retained in its backward position, against the drum, by means of a lock piece V.

When the groups of fibers engaged by each set of blades have been separated as described above, the fork D is swung forward. The teeth r of the fork D are adapted to fit exactly into the channels n while the recesses u between the teeth correspond to the channels m, so that when the fork is 85 swung forward its teeth come to rest upon and are caused to firmly press upon the textile fibers in the channels n while the fibers in the channels m remain exposed.

The operator then raises the exposed 90 fibers by means of a knife and he swings them bodily forward, whereupon he rolls them up on a wooden stick such as is usually employed for similar operations. After having rolled up the exposed fibers as far as 95 the points of the blades, the operator swings the fork D backward so as to expose the fibers in the channels n and then he merely has to remove the stick in order to obtain the slivers intended for combing, said slivers 100 being practically free from entwined or bunched fibers.

Claims—

1. Picker device comprising in combination a picker drum, a set of parallel blades 105 carried by said drum, said blades having a sharp point at one end, and means connected with said drum and adapted to enter the spaces between alternate pairs of adjacent blades.

2. Picker device comprising in combination a picker drum, a plurality of sets of

blades, means for securing said set of blades to the periphery of said drum, and means pivoted to said drum and normally held against the periphery thereof between consecutive sets of blades, said means being adapted to enter the spaces between alternate pairs of adjacent blades.

3. Picker device comprising in combination, a set of parallel pointed blades, a support for said blades, means for securing said blades to said support, a grooved piece of metal secured to the rear upper edge of said support, a picker drum, and means for attaching said support to said drum.

15 4. Picker device comprising in combination, a plurality of sets of pointed blades, supports for said blades, a picker drum, means for attaching said supports to the periphery of said drum, swinging forks arranged one
20 behind each set of blades and adapted, when swung forward, to fit into the spaces between the said blades.

5. Picker device comprising in combination a plurality of sets of parallel pointed blades, supports for said blades, a picker drum, means for attaching said supports to the periphery of said drum, bearings arranged in pairs and secured to the drum behind each set of blades, and swinging forks mounted to swing in said bearings, said forks having teeth adapted to fit into the channels between the blades and the spacing between the consecutive teeth being substantially equal to that between the consecutive blades.

55 five blades.

6. Picker device comprising in combination a set of elongated blades having a sharp point at their forward end and a sharp upper edge throughout their length, a support
40 for said blades, a picker drum, and means for attaching said support to said drum.

7. Picker device comprising in combination a set of blades having a sharp point at their forward end and a sharp upper edge throughout their length, a metal holder for supporting the front portion of said blades, the arrangement being such that the points of the blades project in front of said holder, a wooden support for supporting the rear portion of said blades, a grooved metal piece secured to, and extending along the rear upper edge of said support, a picker drum, and means for attaching said support to said drum.

55 8. Picker device comprising in combination a set of blades having a sharp point at their forward end and a sharp upper edge throughout their length, a support adapted to hold said blades slightly spaced apart
60 from and parallel to each other, said support having a metal front portion and a

wooden rear portion, means for securing the said blades to the said support, a picker drum and means for attaching the said supports to the periphery of the said picker drum. 65

9. Picker device comprising in combination a picker drum, a plurality of picker members secured to the periphery of said drum, each of said picker members comprising a set of blades having a sharp point at their forward end and a sharp upper edge throughout their length, and a support adapted to hold said blades spaced apart and parallel to each other, the arrangement 70 being such that the points of the blades project in front of the support, bearings secured to the drums in close proximity to and behind each picker member, swinging forks mounted to swing in said bearings, said 75 swinging forks being adapted to lie flat against the drum when in their rearward position and engage with their teeth the spaces between the parallel blades when in their forward position, the spacing of the 80 teeth of said forks being substantially equal to that between consecutive blades, and means for locking the said forks in their rearward 85 position.

10. Picker device comprising in combination a picker drum, a plurality of picker members secured to the periphery of said drum, each of said picker members comprising a set of parallel steel blades having a sharp point at their forward end and a sharp upper edge throughout their length, and a support for said blades comprising a front portion of metal, a rear portion of wood and a grooved piece of steel arranged immediately behind the said blades along the rear upper edge of the said wooden portion, the arrangement being such that the points of the blades project in front of the support, bearings secured to the drum in close proximity to and behind each picker member, swinging forks mounted to swing in said bearings, said swinging forks being adapted to lie flat against the drum when in their rearward position and engage with their teeth the spaces between the parallel blades when in their forward position, the spacing of the teeth of said forks being substantially equal to that between consecutive blades, and means for locking the said forks in their rearward position. 115

In testimony whereof I affix my signature
in presence of two witnesses.

CHARLES JEAN NICOUD.
